Primary Examiner — Shannon W Morgan*Assistant Examiner* — Terilyn Nicole Davis(74) *Attorney, Agent, or Firm* — Daniel M. Cohn; Howard M. Cohn(57) **CLAIM**

The ornamental design for a food blender, as shown and described.

DESCRIPTION

FIG. 1 is a perspective view of a food blender showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is an exploded perspective view of the food blender. The broken lines in the drawings depict portions of the food blender that form no part of the claimed design.

1 Claim, 9 Drawing Sheets(56)
